CLAIM

The ornamental design for a boot, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front right-side perspective view of a first embodiment of a boot showing our new design;

FIG. 2 is a front perspective view thereof;

FIG. 3 is a rear perspective view thereof;

FIG. 4 is a right-side perspective view thereof;

FIG. 5 is a left-side perspective view thereof;

FIG. 6 is a top perspective view thereof;

FIG. 7 is a bottom perspective view thereof;

FIG. 8 is a front right-side perspective view of a second embodiment of a boot;

FIG. 9 is a front perspective view thereof;

FIG. 10 is a rear perspective view thereof;

FIG. 11 is a right-side perspective view thereof;

FIG. 12 is a left-side perspective view thereof;

FIG. 13 is a top view thereof; and,

FIG. 14 is a bottom view thereof.

FIGS. 1-14 depict a first and second embodiment of a design for a boot; a third and fourth embodiment are left boots, which are mirror images of the preceding embodiments thereof.

The broken lines appearing in FIGS. 1-14 are to show the environment and form no part of the claimed design.
